UNITED STATES PATENT OFFICE.

LEVI K. SMEDES, OF NEW YORK, N. Y., ASSIGNOR TO THE TAYLOR COMPANY,
OF SAME PLACE.

DESIGN FOR A BURIAL-CASKET.

SPECIFICATION forming part of Design No. 21,582, dated May 24, 1892.

Application filed April 7, 1892. Serial No. 428,234. Term of patent 3½ years.

To all whom it may concern:

Be it known that I, LEVI K. SMEDES, a citizen of the United States, residing at New York, in the county and State of New York, have 5 invented and produced a new and original Design for Caskets, of which the following is a specification, reference being had to the accompanying drawing, forming part thereof.

This design has for its object to provide a 10 novel and ornamental casket which presents to the eye a characteristic and distinguishing appearance, and the leading feature of the design resides in a casket having rounded upper edges at the corners, inclined faces at 15 the lower edges of the corners, and vertical beads interposed between the rounded upper edges and the inclined faces.

The design is illustrated by the accompanying drawing, in which the figure is a perspective view of the casket.

The lid of the casket or coffin has a flat top

A, with an inclined edge B and a bead C, and the casket has rounded upper edges D, enlarged at the corners E. Under the edges D are the offsets F and inclined faces G, and 25 at the corners are beads H. At the lower edge of the casket are the inclined faces I, the offsets K, and the bead L above the base M.

All the corners of the casket are set out from the body in the manner of pilasters. 30

What I claim as new, and desire to secure by Letters Patent, is—

The design for a casket, substantially as herein shown and described.

In testimony whereof I have hereunto set 35 my hand in the presence of two subscribing witnesses.

LEVI K. SMEDES.
